DESIGN FOR A COMBINED JACKET AND ATTACHED CAP

Irving Gerstman, Buffalo, N. Y.

Application February 7, 1936, Serial No. 61,030

Term of patent 14 years

To all whom it may concern:

Be it known that I, Irving Gerstman, a citizen of the United States, residing at Buffalo, in the county of Erie and State of New York, have invented a new, original, and ornamental Design for a Combined Jacket and Attached Cap, of which the following is a specification, reference being had to the accompanying drawing, forming part thereof.

The design consists of a toque or hockey type of cap having a reversely turned adjustable brim as shown and a panel connected at its lower edge with the neck of a jacket and its upper edge

connected with a portion of said brim and forming a neck protector.

In the accompanying drawing:

Fig. 1 is a perspective of a combined jacket and attached cap embodying my new design, viewed from the front.

Fig. 2 is a perspective view, viewed from the rear thereof.

I claim:

The ornamental design for a combined jacket and attached cap, as shown and described.

IRVING GERSTMAN.
